UNITED STATES PATENT OFFICE.

JOHN J. LAMB, OF DETROIT, MICHIGAN.

COMBINED KEROSENE VAPORIZER AND MANIFOLD.

1,217,781.

Specification of Letters Patent. Patented Feb. 27, 1917.

Application filed February 19, 1916. Serial No. 79,271.

To all whom it may concern:

Be it known that I, JOHN J. LAMB, a citizen of the United States, residing at Detroit, county of Wayne, State of Michigan, have invented a certain new and useful Improvement in Combined Kerosene Vaporizers and Manifolds, and declare the following to be a full, clear, and exact description of the same, such as will enable others skilled in the art to which it pertains to make and use the same, reference being had to the accompanying drawings, which form a part of this specification.

My invention relates to a combined kerosene vaporizer and manifold for internal combustion engines, as shown in the accompanying drawings and more particularly set forth in the following specification and claims.

One of the objects of my invention is to provide a simple and inexpensive device, by which kerosene or other hydrocarbon oils may be vaporized on their passage to the combustion chamber of an engine by the heat of the exhaust gases discharged from the latter, that it may be used as the principal fuel in the operation of an engine.

Another object is to combine the device with a manifold connected directly with the inlet ports of an engine:—the exhaust ports of the engine being also an integral part thereof, that it may thus receive not only the heat from the exhaust gases discharged from the engine, but the heat radiated from the cylinders. By thus combining the manifold with the vaporizer, the cost of manufacture and the space required to install the device is materially reduced.

Another feature of the invention consists in providing a plurality of conduits, relatively small in cross section, but of extended length, around which the exhaust gases pass from the engine on their way to the muffler or other point of discharge;—thus the fuel is broken up in its passage that it may be exposed to the heat of the exhaust and receive the maximum radiation therefrom. These several conduits open at one end into a header where the gases commingle and from thence pass directly into the manifold proper,—which being connected adjacent to the intake ports of the respective cylinders, and contiguous to the several exhaust ports leading therefrom, serves as a superheater for the gases prior to their

entry into the combustion chambers of the engine.

Other advantages and improvements will hereafter appear.

In the drawings accompanying this specification:—

Figure 1 is a side elevation of the device, showing the main inlet conduit and the exhaust conduit broken away.

Fig. 2 is a longitudinal central section through the device shown in Fig. 1.

Fig. 3 is a cross sectional view through the device on line 3—3 of Fig. 1.

Fig. 4 is a cross sectional view on line 4—4 of Fig. 1.

Referring now to the letters of reference placed upon the drawings:—

A, denotes a chambered casting flanged at each end. B, indicates a fuel inlet conduit bolted to one end of the casting connecting with a carburetor (not shown). adapted for both kerosene and gasoline.

C, is an arc-shaped casting bolted to the opposite end of the chambered casting A, having an upstanding wall C', spaced therefrom to form a header C²,—the wall being perforated to receive and support a plurality of pipes D. d, is a gasket lodged between the arc-shaped casting C, and the chambered casting A, and d', is a similar gasket between the latter and the flanged wall of the fuel inlet conduit B, to respectively provide a tight joint at these points. The pipes D, are supported at their opposite ends in thimbles E, screwed into the end wall A', of the casting.

F, is a conduit or manifold opening into the chamber or header C², extending adjacent to the chamber A², in which are lodged the pipes D.

G, G, are inlet ports connecting the manifold F, with the respective cylinders of the engine (not shown).

H, H', H², and H³ are ports connecting the exhaust ports of the engine with the chamber A². H⁴, is an exhaust port leading from the chamber A², to the muffler (not shown) or other point of discharge.

I, denotes webs connecting the walls of the respective ports as indicated in Fig. 1;—the webs having openings I', for the passage of bolts to secure the device to the wall of the respective cylinders.

Having indicated the several parts of my invention by reference letters, its construc-

tion and operation will be readily understood.

Following the usual practice in engines employing kerosene or like oils for fuel, 5 the engine is primarily started with gasoline as a fuel. Upon the vaporizer becoming sufficiently heated through the passage of the exhaust gases, the gasoline supply is cut off, and kerosene or other hydrocarbon 10 oils introduced instead.

The fuel in passing through the respective tubes D, is subjected to the heat of the exhaust gases surrounding the several tubes on its passage to the point of discharge. 15 Upon the fuel gas being delivered into the header C², it commingles and passes from thence into the manifold F, above, where it is super-heated by the heat radiating from the cylinder combined with the heat of the 20 exhaust gases passing down through the several ports H', lying adjacent to the manifold;—the fuel gas then passes through the inlet ports G, G, to the respective combustion chambers of the engine.

25 Having thus described my invention, what I claim is:—

1. In a device of the character described, a casting having two independent chambers in adjacent relation, one of which is adapted 30 to communicate with the inlet ports of an engine to serve as a manifold, therefor, a plurality of fuel pipes supported in the other chamber of the casting, an inlet conduit secured to one end of the chambered casting for conducting fuel to said pipes, a header secured to the opposite end of the chambered casting and communicating with the manifold chamber of the latter to deliver thereto the gas discharged from said pipes 35 into the header, a plurality of exhaust conduits integral with the chambered casting in adjacent relation with the wall of the manifold chamber and opening into the chamber in which the fuel pipes are lodged, 40 and a conduit for the discharge of the exhaust gases from said last named chamber.

2. In a device of the character described, a casting adapted to be secured directly to the wall of an internal combustion engine 45

having two independent chambers in adjacent relation to each other, one of said chambers serving as a manifold and adapted for direct communication with the inlet ports of an engine, a plurality of conduits integral with said casting and adjacent to 50 the wall of the manifold chamber for connecting the exhaust ports of an engine with the other chamber of said casting, a conduit for the discharge of the exhaust from said last named chamber, a plurality of fuel 55 pipes located within said last named chamber, a header secured to one end of the casting adapted to establish communication between the pipes and the manifold chamber, and a fuel inlet conduit secured to the opposite end of the casting for the delivery of 60 fuel to said pipes.

3. In a device of the character described, a casting adapted to be secured directly to the wall of an internal combustion engine 70 having two independent chambers in adjacent relation to each other, one of which serves as a manifold and is adapted for direct communication with the inlet ports of an engine, a plurality of conduits integral 75 with said casting and adjacent to the wall of the manifold chamber to connect the exhaust ports of an engine with the other chamber of said casting, webs spaced from the wall of the chambered casting connecting the walls of said conduits together and perforated for the passage of bolts to secure the chambered casting to the wall of an engine, a plurality of fuel pipes located within 80 said last named chamber, a conduit for the 85 discharge of the exhaust gases from the latter chamber, a header secured to one end of the casting adapted to establish communication between the pipes and the manifold chamber, and a fuel inlet conduit secured to 90 the opposite end of the casting for the delivery of fuel to said pipes.

In testimony whereof I sign this specification in the presence of two witnesses.

JOHN J. LAMB.
